UNITED STATES PATENT OFFICE.

SIDNEY C. HILLS, OF TORRINGTON, CONNECTICUT, ASSIGNOR TO THE TURNER & SEYMOUR MANUFACTURING CO., OF TORRINGTON, CONNECTICUT, A CORPORATION OF CONNECTICUT.

CURTAIN-FIXTURE.

1,324,450.

Specification of Letters Patent.

Patented Dec. 9, 1919.

Application filed September 20, 1916. Serial No. 121,124.

To all whom it may concern:

Be it known that I, SIDNEY C. HILLS, a citizen of the United States, and resident of Torrington, county of Litchfield, State of Connecticut, have invented certain new and useful Improvements in Curtain-Fixtures, of which the following is a specification.

My invention relates to curtain fixtures and has for its object to provide an improved bracket and rod construction whereby the sash rod is firmly and efficiently held in position and yet is easily disconnected from the brackets or dismantled when desired. A further object of my invention is to provide an arrangement whereby the sash rod may be located either inside of the casing or outside thereof as desired or found necessary. Other objects of my improvement will appear from the description hereinafter and the features of novelty thereof will be pointed out in the appended claims.

In the accompanying drawings which illustrate an example of my invention, Figure 1 is a plan view; Fig. 2 is an end view; Fig. 3 is a section on the line 3—3 of Fig. 1; Fig. 4 is a front elevation showing my improved construction located inside of the casing; Fig. 5 is a face view showing another form of construction and Fig. 6 is a sectional view thereof on the line 6—6 of Fig. 5.

As shown in Figs. 1 to 4 inclusive of the drawings my improvement comprises brackets each consisting of a plate or other fastening member 5 adapted to be attached to the window, door or other casing 6 in any suitable manner as by means of screws 7. Each plate 5 is provided with a stud or post 8 which projects outwardly therefrom as shown in the drawings and has its outer end recessed to form a socket 9 as illustrated in Fig. 3. In addition each bracket includes a hook or the like 10 which may be secured to the stud or post 8 in any suitable manner as by having its one end constructed as an eyelet 11 and located in an annular groove 12 formed in the stud 8 between the base and recessed end thereof. With this arrangement each hook 10 extends downwardly from its stud or post at an intermediate point and then upwardly in the form of an upright member 10^a in front of and at a distance from the recessed end of each stud or post, the free end of each member 10^a being

preferably curved as shown in Fig. 3. The upright member 10^a is thus resiliently supported and is movable toward and away from the stud or post 8, the recessed end of the latter in the illustrated example being located between the member 10^a and the eyelet 11.

By referring to Figs. 5 and 6 it will be seen that the studs or posts 8 instead of being solid members as illustrated in Figs. 1 to 4 and secured in position on the plates 5 as shown in these figures, may comprise tubular members 8^a having opposite end flanges and serving to clamp the eyelets 11 of the hooks 10 upon the plates 5. These members 8^a in their initial condition do not have the flange at their inner ends and are passed through the eyelets 11 and through suitable openings in the plates 5 after which the inner end of each member 8^a is turned down or otherwise manipulated to produce the inner end flange shown in Fig. 6. In this manner the eyelets 11 of the hooks 10 are securely clamped between the outer end flanges of the members 8^a and the plates 5 and the members 8^a are themselves firmly combined with said plates. With this arrangement the ends of the axial passages which terminate in the free ends of the members 8^a form sockets 9^a corresponding to the sockets 9 of Figs. 1 to 4; otherwise the construction and operation of this form of my improvement may be the same as in the form first described.

In any case the fixture further comprises a rod 13 which may be made in sections so as to be extensible in any customary manner or of fixed length as desired and in either case may be provided at opposite ends with spherical members 14 which are provided with centrally located diametrical apertures 15 as shown in Fig. 3. These apertures 15 are adapted to receive and accommodate the members 10^a of the hooks 10 when the rod is combined with the brackets whereby said rod is supported in operative position on the casing 6.

It will be seen, when the rod 13 is operatively connected with either of the illustrated brackets that the spherical end members 14 rest in the sockets 9 or 9^a of the studs 8 or posts 8 or 8^a as the case may be, the recessed surfaces forming the sockets 9 preferably fitting the peripheries of the members

14 as illustrated in Fig. 3. The parts are preferably so constructed and proportioned that as the end members 14 are forced home upon the members 10^a of the hooks 10, the 5 said members will be placed under a tension tending to force the end members 14 of the rod 13 into the sockets 9 or 9^a and to maintain them therein. The said rod 13 is thus firmly held upon the posts 8 or 8^a and securely fastened in operative position against 10 unintentional separation relatively to the brackets and yet may be readily disconnected therefrom by simply exerting an upward pressure sufficient to overcome the 15 tension exerted by the members 10^a.

Owing to the fact that the apertures 15 are located centrally of the spherical end members 14 the rod may be located either outside of the casing 6 as shown in Fig. 1 or 20 within the same as shown in Fig. 4. All that is required to secure either result is to fasten the brackets either to the front faces of the casing 6 as in Fig. 1 or to the opposite inside surfaces thereof as in Fig. 4.

25 It will be seen that, in all cases when the rod is operatively connected with the brackets, the posts or studs 8 and 8^a are always in line with the ends of the rod, this arrangement providing an extremely neat 30 appearance and resulting in a maximum of resiliency and efficiency in the parts.

It will be readily apparent that instead 35 of providing the spherical end members 14, projections having simply a curved surface adapted to fit into the sockets 9 or 9^a may be provided, while if found convenient or necessary any desired shape of end projection may be used, the sockets 9 and if necessary the sockets 9^a being shaped to properly receive and accommodate the same. Similarly 40 the end members 14 of the rod 13 may be hollow instead of solid, and provided with diametrically opposite apertures instead of continuous apertures 15 extending 45 diametrically therethrough.

It will also be obvious that the location of the sockets and projections with respect to the brackets and rod may be reversed if desired, the improvement merely requiring co-operating surfaces or other elements on the rod and brackets respectively in combination and means for holding these surfaces in engagement with each other, in order to work satisfactorily and efficiently. With 50 the type or construction shown in Figs. 1 to 4 inclusive, or equivalent arrangement, it is also possible to obtain different positions of the curtain rods with respect to the window or other casing by increasing or diminishing 55 the axial length of the posts 8 as will be apparent. It will further be obvious that the posts may extend outwardly from the plates 5 in directions other than a substantially perpendicular direction thereto.

60 65 The arrangement is extremely simple in

construction with a maximum of efficiency and is of a highly ornamental and attractive appearance when in use. The peculiar construction of the brackets and rod results in an operative combination thereof which provides a harmonious continuity of structure without any harsh or unattractive breaks in the lines between the brackets and rod. In fact when in use the combined brackets and rod have the appearance of a single unit. 70 All parts of the invention are easy and simple to construct thus insuring a low cost of production without in any way interfering with the efficiency or the attractiveness of the fixture. 75

Various changes in the form shown and described may be made within the scope of the claims without departing from the spirit of my invention.

I claim:

1. In a curtain fixture, the combination of a bracket, a curtain rod, a member on one of said elements having a recessed surface, a device on the other element having a co-operating surface arranged to fit said recessed surface whereby said member and device are positioned in fixed relation to each other with said device in alinement with the center of said recessed surface and resilient means carried by said bracket and exerting 90 a tension whereby said recessed surface and co-operating surface are maintained in engagement with each other.

2. In a curtain rod, the combination of a bracket fastening member, a substantially 100 rigid post extending outwardly therefrom and having an outer free end, a curtain rod provided with a transverse aperture, co-operating surfaces at said free end of the post and at an end of the rod respectively whereby said post and rod are positioned in fixed relation to each other with the co-operating surface on the end of said rod in alinement with said post and a member carried by said post and extending into the aperture of said 105 rod whereby said co-operating surfaces are maintained in engagement with each other.

3. In a curtain fixture, the combination of a bracket, a substantially rigid post forming a part thereof and having its end face recessed, a curtain rod, an end member on said rod having a surface arranged to fit said recessed end face of the post for detachably combining said rod and bracket and means whereby the recessed free end of the post and the surface of said end member are maintained in engagement with said end member in alinement with said post and a separation of said bracket and rod is resisted.

4. In a curtain fixture, the combination of 125 a bracket comprising a fastening member, a substantially rigid post projecting outwardly from the outer face thereof and having its end face recessed, a curtain rod, an end member on said rod having a surface 130

arranged to fit said recessed end face of the post for detachably combining said rod and bracket and provided with an aperture and a resilient hook carried by said post and 5 extending through said aperture whereby the recessed end face of the post and the surface of said end member are maintained

in engagement with said end member in alinement with said post and a separation of said bracket and rod is resisted.

10

In testimony whereof I have hereunto set my hand.

SIDNEY C. HILLS.
